UNITED STATES PATENT OFFICE

ANDRE HUET, OF PARIS, FRANCE, ASSIGNOR TO THE SUPERHEATER COMPANY, OF NEW YORK, N. Y.

REHEATER

Application filed November 30, 1928, Serial No. 322,870, and in France April 30, 1928.

This invention relates to reheaters in which interstage steam, that is, steam from one stage of an engine flowing to the subsequent stage where it is to expand further, is reheated by means of superheated live steam of higher pressure and temperature before being delivered to the second stage. The invention has for its purpose the provision of apparatus of this type which shall be more economical in construction and operation than devices of this type have been heretofore and which shall have certain other advantages appearing from the following specification.

The invention is illustrated in the two sheets of drawings herewith, in which Fig. 1 is a vertical, central section of an apparatus according to my invention; Fig. 2 is a section on line 2—2 of Fig. 1, certain portions being omitted for the sake of clearness; Fig. 3 is a view on a larger scale of a portion of Fig. 1; Fig. 4 is a vertical, central section of a second form of the invention; Fig. 5 is a section on line 5—5 of Fig. 4; and Fig. 6 is a section on line 6—6 of Fig. 5.

Referring first to the form of my invention illustrated in Figs. 1, 2 and 3, 1 is a casing or drum through which flows the fluid to be heated. This fluid, as mentioned above, is ordinarily interstage steam which will usually enter in a saturated form and leave the casing in a superheated condition. The steam enters at 2 and leaves at 3. The baffle 4 causes it to flow first upward over the upper edge of the baffle and then downward. The fluid by which the interstage steam is to be heated enters the header 5, this header having connected to it a number of serpentine or zig-zag coils 6—6 which lie in the upper portion of the upward pass between the casing and the baffle 4. These serpentine coils 6 are of small internal diameter so that the flow of the steam through them is comparatively very rapid.

Each of these serpentines 6 is connected by

means of a tube 7 to a header 8. These headers 8 are arranged in a parallel position in the lower portion of the pass and at right-angles to the header 5. Connected to each header 8 is a series of vertical tubes 9—9, the upper ends 10—10 of which are closed, as will be more clearly seen in Fig. 3 where one of these other headers 8 with the connected pipes is illustrated on a larger scale. Below the headers 8 and transversely to them is arranged a pipe 11 to which the headers 8 are connected by means of the pipes 12. The outlet from this pipe 11 is shown at 13, Fig. 2.

The steam entering the header 5 is, as mentioned above, superheated steam of a pressure higher than the interstage steam. The transfer from superheated steam is difficult and is enhanced by causing it to flow rapidly through the serpentines 6. By the time the steam reaches the lower headers 8 through pipe 7, the superheat has disappeared and the steam enters these headers 8 in its saturated condition. The size necessary for the serpentine coil 6 can be quite accurately computed when the several conditions under which the apparatus is to work are known. When once in saturated condition the steam gives up heat by condensing, and this latent heat of vaporization is given up very readily. While rapid flow might also facilitate heat transfer at this stage, the friction losses caused by such greater velocity would much more than offset the gain. In my apparatus, therefore, I eliminate rapidity of flow entirely and permit the steam to condense under practically stagnant conditions. As the steam condenses, the resulting condensate flows down the sides of the tubes 9 into the headers 8, being replaced by other steam that enters at the lower ends of the tubes 9 and rises up into them. This flow of the steam is comparatively very slow and no appreciable losses are encountered.

The condensate collecting in the header 11 is removed from the connection 13.

The nature of my invention will now be understood. It consists essentially in causing the heating steam to flow at a high rate of speed as long as it is superheated, and keeping it in a practically stagnant condition while it is giving up its latent heat of vaporization.

A second form for carrying out my invention is illustrated in Figs. 4, 5 and 6. The steam to be heated in this apparatus enters at 2^a and is directed by suitable baffling toward the outlet 3^a, its flow being indicated by the arrows in Fig. 4. The superheated high pressure heating steam enters the header 5^a (which in this case lies outside of the casing 1^a). The serpentine coils 6^a—6^a are connected to this header 5^a and deliver the steam flowing through them to the headers 14—14. It will be noted that in this arrangement two serpentine coils 6^a—6^a connect to each header 14. This is a matter of choice and under some conditions it may be preferable to have only one connected to each header. From the headers 14—14 extend downwardly the bifurcated elements 15—15, their lower ends opening into the headers 8^a—8^a. To these headers 8^a—8^a are connected the pipes 12^a—12^a leading outward through the casing 1^a and connecting to the pipe 11^a. It will be seen that in this form also the flow of the steam through the serpentine coils 6^a—6^a is comparatively very rapid while the flow through the bifurcated elements 15—15 is comparatively very slow, the steam being substantially stagnant in these units. The dimensions of the several portions of the apparatus are here also so computed that the heating steam arrives in the headers 14—14 in a saturated condition and that it is all condensed by the time the steam reaches the headers 8^a—8^a.

Obviously the apparatus can be modified in various further ways without departing from its spirit.

45 I claim:

1. In apparatus of the class described, the combination of a shell, an inlet to and an outlet from said shell, whereby steam to be superheated may be circulated through the shell, a conduit extending through but not opening into the shell, means to supply superheated steam of higher pressure than the steam flowing through the shell to the inlet of the conduit, and means to remove condensate from its outlet, the conformation of said conduit being such that adjacent to its inlet the steam flow through it is rapid while further on the steam is substantially stagnant.

2. In apparatus of the class described, the combination of a conduit, means to supply superheated steam to its inlet, means whereby a heat absorbing fluid may be brought into contact with said conduit, and means to remove condensate from its outlet, the conduit being of such conformation that, for a

given set of initial temperature and pressure conditions of the two fluids, as long as the steam is superheated its flow is rapid and that after it is saturated its flow is relatively slow.

3. In apparatus of the class described, the combination of a conduit, means to deliver superheated steam to its inlet, means to remove condensate from its outlet, the conformation of the conduit being such that through the first portion of its length the steam flow is rapid while in the remaining portion the steam is substantially stagnant, and means to cause a heat absorbing fluid to flow in contact with the outside of the conduit, the relative proportions of the two portions of the conduit being such that, for a given set of initial temperature and pressure conditions of the steam, and of the heat absorbing fluid the steam enters the second portion in a substantially saturated condition.

4. Apparatus in accordance with claim 3, the relative proportions further being such that the steam is all condensed by the time it reaches the outlet.

5. In apparatus of the class described, the combination of a horizontal header, a plurality of aligned tubes opening from it and extending vertically upward, the upper ends of said tubes being closed, a serpentine coil above and in the plane of said tubes, and means placing the lower end of said coil into communication with the header.

6. Apparatus comprising in combination a plurality of structures as claimed in claim 5, said structures being arranged side by side, a shell enclosing said structures, means to supply superheated steam to said coils, means to remove condensate from said headers, and means to cause low pressure steam to flow through said shell in contact with said structures.

7. In apparatus of the class described, the combination of a plurality of similar conduits, means to deliver superheated steam to their inlets, means to remove condensate from their outlets, the conformation of each conduit being such that through the first portion of its length the steam flow is rapid while in the remaining portion the steam is substantially stagnant, the portions of each conduit being in a single plane and the several conduits being arranged side by side, a shell enclosing said conduits, and means to cause steam of a lower pressure than that in the conduits to flow through the shell in contact with said conduits.

8. The method of desuperheating and condensing steam comprising the steps of cooling it to its saturation point by causing it to flow at a relatively high velocity through a conduit surrounded by a heat abstracting medium, and then condensing it while it is substantially stagnant.

9. The method of desuperheating and con-

densing superheated steam of relatively high pressure while superheating steam of lower pressure, comprising the steps of causing the superheated steam to flow at relatively high velocity in heat transferring relation to but out of contact with the low pressure steam until the superheat is given up, and thereafter to keep the two steams in such heat transferring relation with the high-pressure steam substantially stagnant until it is condensed.
